CHARLES W. EDDY, OF EAST PROVIDENCE, RHODE ISLAND

TYPE-CASTING MACHINE

Application filed October 13, 1928. Serial No. 312,230.

This invention relates to type casting machines, and the primary object thereof is to provide an improved mold for regulating the length and thickness of slugs, types, ornaments, logotypes, printer's furniture and the like, and more particularly a mold which is automatically adjustable for regulating the length and thickness of slugs, etc.

A further object of the invention is to provide a mold which can be easily and quickly substituted for molds employed in casting machines of a well known type now in general use, and which is also susceptible of use with other power or hand operated machines.

15 In the drawings:—

Figure 1 is a perspective view of the invention applied to a machine of common or well known type;

Figure 2 is a longitudinal sectional view taken through the mold and showing the jaws in inoperative position;

Figure 3 is a view similar to Figure 2 showing the jaws in operative position and engaging the size regulating pieces, which latter are assembled in the stick;

Figure 4 is a view similar to Figure 1 showing the parts in casting position, the size regulating pieces being cutaway to show their position in the mold;

Figure 5 is a longitudinal sectional view of Figure 4 showing the position of the parts after casting;

Figure 6 is a view similar to Figure 5, but showing the jaws open before the mold descends from the matrices and also showing the fin attached to the type;

Figure 7 is a sectional view showing the parts during the downward position of the mold and illustrating the type or slug firmly held in the latter by the fin;

Figure 8 is a sectional view of the finished type or slug showing the fin removed therefrom;

Figure 9 is a detail view showing a large size of regulating piece employed to thicken the type or slug;

Figure 10 is a view similar to Figure 9 illustrating the invention in connection with the type wherein the body thereof is smaller than that of the face of the type;

Figure 11 is a detail view showing the matrices assembled in the stick and a slug cast from the matrices;

Figure 12 is a view similar to Figure 11, but showing size regulating pieces between some of the matrices and also the cast type, and

Figure 13 is a detail perspective view of one of the size regulating pieces.

In proceeding in accordance with the present invention a mold 1 is employed which is formed to seat on a top plate 2. The mold is provided with slideable spring pressed jaws 3 and 4, and accordingly the jaw 3 is provided with a pin 5 having a coil spring 6 thereon, the pin being secured to the jaw at one end and at its opposite end being headed and slidably received through the rear end 7 of the mold frame 1. A similar pin 8 is secured to the jaw 4 and is surrounded by a coil spring 9, the pin being headed and extending through a slideable block 10 disposed within the mold frame. The block 10 has openings in its sides to loosely receive the inner ends of dogs 11, the latter being pivoted at 12 and having their outer ends loosely received in openings in the sides of the mold frame 1. A hollow slide 13 is connected to the mold frame 1 by means of a pin 14 headed into engagement with the latter, which pin passes through the rear end of the slide and has a coil spring 15 thereon, the latter pressing against the rear end of the slide. An actuating pin or post 16 is carried by the usual cam device 17 common to casting machines and engages within the adjacent end of the slide 13.

The plate 2 is formed with a slot 18 which latter registers with the space between the jaws 3 and 4 and which is also adapted to register with the mouth piece 19 of the casting machine. The usual jets of the machine are illustrated at 20 in Figure 1.

In order to adapt the present invention to machines in common usage, the only alteration of the machine required is that of removing the mold thereof and substituting the present invention, and the securement of the pin 16 to the cam device.

The size regulating pieces 20 are shown in Figure 13 and have depending shanks 21.

In operation, and referring to Figure 11, the stick 22 is formed by first placing a size regulating piece 20 therein and then assembling the matrices 23 to form the desired work, following which a second size regulating piece of such length as to cover any exposed jets is placed in the stick and all of the parts are then firmly secured by means of the thumb screw 24. Figure 12 illustrates the formation of the stick for casting single letters or numerals by first placing a size regulating piece in the stick, then a matrix 23, then a size regulating piece, etc., or in other words, the size regulating pieces and matrices alternate, and finally a size regulating piece of the desired length is added to the stick and the screw 24 tightened as above described.

After the stick has been formed as above described, it is locked in the opening of the usual cover of the machine and the latter is started. At this time the parts are in the position of Figure 2, and after the mold moves upwardly the pin 16 moves outwardly from the mold as shown in Figure 3, causing the jaws 3 and 4, by reason of the movement of the frame acting on the dogs 11-11, to grip the two sides of the shank 21 of the size regulating piece, so as to securely hold the latter. When the mold reaches its extreme upward position, the melting pot is beneath the plate 2 and the jets 20 are in alignment with the slot 18 of the plate 2. The melted metal is then forced through the jets and slot 18 into the mold and matrices as shown in Figure 5, resulting in casting of the type 25. Completing the cycle, the pot moves to one side, the plate 2 moves downwardly and the pin 16 moves into the position of Figure 6, in which same is disengaged from the slide 13, releasing the pressure on the dogs 11-11, causing disengagement of the jaws 3 and 4 from the cast type, thereby releasing the latter. However, the type is still held in the mold by the fin 26 which is integral therewith and which results from the molding as is obvious. The plate 2 and the mold then continue to move downwardly until the fin 26 has been severed by a knife common to machines of this type, at which time the cast type is lifted out of the mold, conveyed from the machine by mechanism, also common to machines of this type.

In Figure 8 is shown the completed type 25 from which the fin 26 has been removed.

Figure 9 shows larger size regulating pieces employed to thicken the body of the type so as to make same larger than the size of the type, thus eliminating the necessity of spacing between the slugs during printing, while Figure 10 illustrates the body of the type of less thickness or diameter than that of the face of the type.

Having thus described my invention what

I claim as new and desire to secure by Letters Patent is:—

1. In a casting machine, a mold, a slidable spring pressed jaws in the mold, operating means for one of the jaws to move same toward the other jaw, a spring pressed slide connected to said operating means, and a pin formed for connecting with the cam device of the machine to operate the slide. 70

2. In a casting machine, a mold, a slidable spring pressed jaws in the mold, operating means for one of the jaws to move same toward the other jaw, means to actuate said operating means, and means operable by the cam device of the machine to operate said actuating means. 75

3. In a casting machine, a mold, a pair of opposed gripping jaws, independent spring means to tension each jaw, and spring means to actuate the jaws to cause same to move into and out of gripping position. 80

4. In a casting machine for use with type size regulating pieces, a mold, means associated with the mold to releasably grip said pieces, means to actuate said gripping means, and spring means to tension said gripping means operable independently of said actuating means thereof. 90

In testimony whereof I have hereunto signed my name. 95

CHARLES W. EDDY.
